UNITED STATES PATENT OFFICE

ALBERT FIORI, OF MILWAUKEE, WISCONSIN

DESIGN FOR A FRAME FOR PICTURES, MIRRORS, OR SIMILAR ARTICLES

Application filed May 13, 1929. Serial No. 31,201. Term of patent 7 years.

To all whom it may concern:

Be it known that I, ALBERT FIORI, a citizen of the United States, and resident of Milwaukee, in the county of Milwaukee and State of Wisconsin, whose post-office address is 629 Meinecke Avenue, have invented a new, original, and ornamental Design for Frames for Pictures, Mirrors, or Similar Articles, of which the following is a description, reference being had to the accompanying drawing, forming part thereof.

In the drawing, Figure 1 is a front view of the frame, and Figure 2 is an edge view thereof on a smaller scale.

I claim:

The ornamental design for a frame for pictures, mirrors, or similar articles, as shown.

ALBERT FIORI.
